DRILLING MACHINE

Original Filed May 23, 1921

UNITED STATES PATENT OFFICE.

GEORGE K. GILMAN, OF BELMONT, MASSACHUSETTS.

DRILLING MACHINE.

Application filed May 22, 1921, Serial No. 471,562. Renewed November 30, 1926.

My invention relates to drilling machines having fluid pressure operated power cylinders and particularly but not exclusively to a rock drilling machine having such a device for feeding the drill steel relatively to the rock.

The invention will be best understood from the following description when read in the light of the accompanying drawings of a specific embodiment of the invention selected for illustrative purposes, while the scope of the invention will be more particularly pointed out in the appended claims.

In the drawings:

Fig. 1 is an elevation of a rock drilling machine constructed according to the invention;

Fig. 2 is a central sectional elevation according to Fig. 1 with parts omitted;

Fig. 3 is a section on the line 3—3 of Fig. 1;

Fig. 4 is a section on the line 4—4 of Fig. 2;

Fig. 5 is an arrangement of sections on the lines a—a, b—b and c—c of Fig. 3, illustrating the operation of the valve controlling the feed cylinder.

Referring to the drawings, the drill actuator 1, which may be of any type is shown as a fluid pressure operated percussive hammer for actuating the drill steel 3. As illustrated, the drill actuator is carried on a cradle 5 provided with guides 7 sliding in ways 9 carried by the feed cylinder 11 in order that when motive fluid is admitted to the feed cylinder, the piston thereof which is connected to the actuator may move the drill steel relative to the rock or other work.

The feed cylinder shown comprises a tube 13, the opposite ends of which respectively are closed by the rear feed cylinder head 15 and front feed cylinder head 17, these heads being secured to the tube by means of bolts 19 engaging collars 20 carried by the tube. Herein for supporting the machine the feed cylinder carries the trunnion 21 adapted to be attached to the trunnion support of a tripod or mine column. As the specific nature of the construction of the feed cylinder, trunnion and guide ways do not form part of the present invention, the same will not be further described.

In the feed cylinder is shown a reciprocable piston connected to the drill steel actuator by means forming a piston rod comprising the outer tubular member 23 which con-

tains the inner tube 25. As illustrated, the rod is connected to the actuator by means comprising a member 27 having the end portion 29 of reduced diameter, which enters the end of the tube 23 and forms an exterior shoulder 31 which the end of the tube abuts, the tube and member 27 being secured together in this relation in any suitable manner, preferably by welding. The other end of the member 27 is shown as connected to a projection 33 formed on the upper portion of the drill bit actuator, said projection herein also serving as a valve casing for the controlling valve 35 for the actuator. For making the connection the projection is shown as provided with a rearwardly extending nipple 37 having a frusto-conical exterior end 39 and an intermediate groove 41, the latter providing a shoulder 43, while the rearward end of the member 27 is provided with an interior frusto-conical socket 45 which fits the complementary portion of the nipple. Externally of the socket, the member 27 is screw-threaded and carries the union-nut 47 provided with the flange 49 affording a shoulder for engaging the ring 51 carried in the groove. For enabling the parts to be assembled, the ring 51 is split in one or more places to provide respectively either a ring similar to the ordinary piston ring or a segmental ring.

As illustrated, the controlling valve 35, above referred to, is in the form of a frusto-conical turning plug having the operating handle 53, and the end of the casing 33 for the valve is connected to a source of motive fluid supply by way of the hose connection 55. This connection constantly supplies motive fluid to the internal conduit 57 of the valve and to the radial passage 59 placing said conduit in communication with the exterior surface of the valve. By manipulating the valve handle, the radial passage may be moved into and out of communication with the intake passage 61 of the drill steel actuator to supply it with motive fluid or to interrupt such supply.

Herein the member 27 intermediate its length is so formed as to provide a valve casing 63 for the valve 65 which controls the movement of the feed piston. This valve is of the frusto-conical turning plug type, and is normally held to its seat by means of the spring 67 seated between the interior shoulder 68 of the valve and the cap 69 closing the end of the valve casing. The valve

may be operated by means of a handle 71. Herein, for supplying the valve 65 with motive fluid, the upper end of the valve casing as viewed in Fig. 3 is connected by a passage 75 with the interior of the socketed end 73 of the member 27, and for connecting the socket with the source of motive fluid supply the nipple 37 is shown as formed with a passage 77 communicating with the socket 10 and with a groove 79 formed in the interior wall of the valve casing 33, the groove 79 being intersected by a longitudinal groove 81 which is formed in the wall of the valve casing and terminates adjacent the hose connection.

In the member 27 on the side of the valve 65 opposite the socket 73 is shown a pair of passages 83 and 85, the former establishing communication between the interior of the tube 23 and the seat for the valve 65 and the latter between the tube 25 and said seat. For establishing the connection between the tube 25 and the passage 85, the end of the passage is provided with an enlarged diameter portion 87 which receives the tube and to which it is welded.

Herein the tube 23 is formed to present the straight portions 89 and 91 connected by the bend forming a transverse portion 93, the straight portion 91 entering the interior of the feed cylinder through the perforation 95 in the rear feed cylinder head. In the cylinder the end of the tube is secured preferably by welding to the reduced diameter portion 97 of the tubular member 99. The reduced diameter portion 97 forms a shoulder against which the end of the tube abuts, and against the shoulder formed by the end of the tube abuts one of the sections 101 of the piston, these sections being held in assembled relation by means of the nut 103 cooperating with the screw-threaded end of the member 99. The bore 105 of the member 99 is in free communication with the interior of the tube 23, this bore being reduced in diameter, however, at the rearward end of the member to form a bore 107 which receives and is closed by the tube 25, the interior of the latter opening to the forward side of the piston.

In assembling the piston rod the member 99 is first secured to the outer piston rod tube 23 and the inner piston rod tube to the member 27. The tube 25 is then threaded 55 through the tube 23 until its end passes through the bore 107. The end of the tube 23 is then expanded to form the flange 109 fitting the flared end 111 of the bore 107. To enable the tube 25 to be readily threaded 60 through the tube 23, the former preferably is flexible. Herein the tube is formed with convolutions 113 which produce a flat coil at the portion of the tube fitting the bend in the tube 23. The coiled portion of the 65 tube when threaded through the bend will

engage the walls of the tube 23 and thereby hold the inner tube against vibration and at the same time enables the inner tube to be placed under tension to hold the flange 109 firmly against its seat provided by the flared 70 portion 111.

As illustrated, for controlling the operation of the feeding device, the valve 65 is provided with an internal conduit 115 which communicates with the rearward end of the 75 valve casing and thereby provides that said conduit is in constant communication with the source of motive fluid supply. Referring particularly to Figs. 3 and 5, in the plane of the passage 83 leading to the interior of 80 the outer piston rod tube the valve is shown as formed with the radial passages 117 and 119 which place the conduit 115 in communication with the exterior of the valve. In the same plane as the passage 85 leading 85 to the tube 25 I provide a similar radial passage 121. Adjacent opposite ends of the valve are arcuate grooves 123 and 125, and for placing them in communication with the atmosphere are the passages 127 and 129 90 formed in the valve casing. The groove 125 is in constant communication with the passage 129 and the groove 123 intermittently in communication with the passage 127 as will hereinafter appear. Leading 95 from these grooves toward the center of the valve are respectively grooves 131 and 133 formed on the exterior of the valve and respectively terminating in planes including the adjacent portions of the passages 83 and 100 85. At opposite sides of the passage 119 and in communication therewith are narrow slots 135 and 137, and at one side of the passage 121 a similar slot 139.

The operation of the valve 65 is as follows:—

With the parts in "Neutral" position indicated in Fig. 5, the passages 83 and 85 leading to opposite ends of the feed cylinder are in communication with neither the source 110 of motive fluid nor the atmosphere. If, from this position the valve is turned clockwise to the position indicated by "Slow forward" the passage 83 will be placed in communication with a slot 137, while the passage 85 will be placed more or less depending on the exact position of the valve in communication with the groove 133. In this position the valve supplies a restricted amount of motive fluid to the rear end of 120 the cylinder and permits a restricted exhaust from the front end of the cylinder which causes the feed piston to slowly feed the drill bit towards the work. If from the "Slow forward" position the valve is turned 125 further in a clockwise direction, to the "Full forward" position indicated by Fig. 5, the passage 83 is placed in full communication with the passage 137 and the passage 85 in full communication with the exhaust groove 130

133 which causes the piston to force the drill bit towards the work with a maximum of pressure. If, from the full forward position, the valve is turned further in a clockwise direction, the slot 135 may be brought into communication with the passage 83 and the groove 133 moved to partially communicate with the passage 85 which again restricts the admission to the rear and the 10 exhaust from the front end of the cylinder to decrease the force of the feed.

If the valve is moved from the neutral position to the "Slow reverse" position shown by Fig. 5, the slot 139 is brought into communication with the passage 85 and the passage 117 into communication with the passage 83. This places both ends of the cylinder in communication with the source of motive fluid supply, the supply to the front 20 end being restricted and in consequence of this, the piston by differential action is forced to slowly move the drill steel away from the rock. If from the "Slow reverse" position the valve is moved further in an 25 anticlockwise direction to the "Full reverse" position indicated by Fig. 5, the passage 83 will be placed in communication with the exhaust groove 131 and the passage 85 in communication with the passage 121. This 30 will place the rear end in communication with the atmosphere and the front end in full communication with the motive fluid supply and in consequence the drill bit will be retracted with a maximum of force.

As shown for preventing the piston from violently striking the cylinder heads of the feed cylinder, the front cylinder head is provided with a pin or other projection 141 which is adapted to enter the interior of the 35 tube 25 when the piston approaches the front end of the cylinder. The diameter of the pin is slightly less than that of the interior of the tube in order that it may restrict but not entirely close off communication between 40 the interior of the tube and the end of the cylinder when the piston is at its extreme forward end. Communication between the outer tube of the piston rod and the rear end of the cylinder is provided by a passage 143 45 and a restricted passage 145. When the piston approaches the rearward end of its stroke, the portion of the tube having the passage 143 enters the bore of the front cylinder head which closes said passage and 50 leaves open only the restricted passage 145. It will be noted by these means that I have provided for restricting the exhaust from each cylinder end when the piston approaches the corresponding cylinder head 55 but have not prevented the admission of fluid to such end for moving the piston away from the cylinder head.

It will be noticed that the cylinder heads and opposite faces of the piston provide 60 pairs of pressure abutments of which those

afforded by the faces of the piston are movable and that the forward face of the piston is larger than the rearward face to provide a differential piston and pairs of oppositely facing pressure abutments having relatively 70 different areas.

The invention disclosed herein is an improvement on the invention disclosed in my copending application Serial No. 442,094, filed February 3, 1921. 75

Although I have described one specific embodiment of my invention for purposes of illustration, it is to be understood that wide deviations may be made therefrom without departing from the spirit of my invention. 80

Claims:

1. In a machine of the character described, a percussive tool, a feeding means for said tool comprising a cylinder and piston, said percussive tool being carried by 85 said cylinder in slideable relation thereto, a substantially U-shaped piston rod formed of a bent tube, said rod projecting through the rear end of said cylinder and connecting said piston and percussive tool, a tube of less 90 external diameter than the internal diameter of said rod and having a coiled portion to make it flexible, said tube being inserted through said rod and extending substantially the length of said rod and bearing against 95 the walls of said rod at the bend of said rod, said rod being in fluid communication with one end of said cylinder and said tube with the other end of said cylinder, and means for connecting the interior of said rod and 100 tube with a source of motive fluid.

2. In a machine of the character described, an actuator for a drilling tool, feeding means for said tool comprising a cylinder and piston, said cylinder slidably carrying said actuator, a hollow substantially U-shaped piston rod having two straight portions and a portion connecting said straight portions, said piston rod projecting through the rear end of said cylinder and connecting said piston and actuator, means providing a tubular fluid conduit located interiorly of one of said straight portions, means providing a tubular fluid conduit located interiorly of the other straight portion, a conduit in the connecting portion of said rod connecting said means, a support for each of said means adjacent the connecting portion of the rod, and a connection to a source of motive fluid for admitting motive fluid to one end of said cylinder by way of said hollow piston rod and to the other end of said cylinder by way of said means and conduit. 110

3. In a machine of the character described, a hammer rock drill having provision for carrying a drilling tool, feeding means for said drill comprising a feed cylinder and piston, a hollow piston rod connecting said piston to said drill, the interior 125

- of said rod being in fluid communication with said cylinder at one side of said piston, a tube in said hollow rod, said tube being in fluid communication with said cylinder at the opposite side of said piston, means supporting said tube at one end thereof, a flange at the opposite end of said tube, means providing a seat for said flange, and means placing said tube under tension for holding said flange to its seat.
4. In a machine of the character described, a hammer rock drill, feeding means for said hammer rock drill comprising a cylinder and piston, said hammer rock drill being slidably supported by said cylinder, a hollow substantially U-shaped piston rod extending through the rear end of said cylinder and connecting said piston and hammer rock drill, said piston rod being in fluid communication with the rearward end of said cylinder, a longitudinally resilient tube in said hollow rod in fluid communication with the forward end of said cylinder, means providing a flange carried by said tube adjacent one end of said tube, means providing a seat for said flange, said tube bearing against the walls of said rod at the bend of said U, and means for supporting the end portion of said tube opposite said flange.
5. A machine of the character described having, in combination, a percussive tool, feeding means therefor comprising a cylinder and piston, said cylinder slidably supporting said percussive tool, connecting means between said piston and percussive tool comprising a hollow piston rod having a straight and connected transverse conduit for conducting motive fluid to said cylinder at one side of said piston, and a flexible tube inserted in said rod and passing through said conduit for conducting motive fluid to said cylinder at the opposite side of said piston, said tube bearing against the walls of said transverse conduit.
6. A machine of the character described having, in combination, a percussive tool, feeding means therefor comprising a cylinder and piston, a hollow piston rod connecting said piston with said percussive tool, said rod having a straight and connected transverse conduit, a tube inserted into the conduit of said rod, said tube having a rigid portion in the straight portion of said rod, and a flexible portion in the transverse portion of said rod bearing against the walls of said transverse portion.
7. A machine of the character described having, in combination, a percussive tool, feeding means therefor comprising a stationary cylinder and movable piston, said percussive tool being offset relative to said cylinder with their axial lines parallel, a bent piston rod connecting said percussive tool and piston, a tube extending through
- said rod, said tube having a flexible portion for passing it through the bend of said rod and connections for conducting motive fluid to said cylinder by way of said tube.
8. In a machine of the character described, 70 a percussive tool, means for moving said tool relative to the work comprising a cylinder and piston, a hollow substantially U-shaped piston rod extending through the rear end of said cylinder and connecting said 75 piston to said tool, said rod being in fluid communication with one end of said cylinder, a tube in fluid communication with the other end of said cylinder and located interiorly of said rod, said tube having a flexible 80 portion passing through the bend of said U-shaped rod and bearing against the walls of said bend.
9. A machine of the character described having, in combination, a percussive tool, 85 feeding means therefor comprising a cylinder and piston, said percussive tool being slidably supported in side by side relation with said cylinder, a piston rod formed of a tube bent to a substantially U-shape extending through the rear end of said cylinder and being in fluid communication with one end of said cylinder, and a flexible tube carried interiorly of said rod adapted to conform to said bend when inserted and forced through 90 said rod said tube being in fluid communication with the opposite end of said cylinder.
10. A machine of the character described having, in combination, a percussive tool, 100 feeding means therefor comprising a cylinder, a piston in said cylinder, a hollow piston rod secured to said piston and opening through one side thereof, an open ended tube closing the open end of said rod from communication with said cylinder, said tube 105 communicating with said cylinder at said side of said piston, means placing said rod in communication with said cylinder at the opposite side of said piston, and means for connecting said rod and tube to a source of 110 motive fluid.
11. A machine of the character described having, in combination, a percussive tool, feeding means therefor comprising a cylinder, a hollow piston rod having an exterior 115 shoulder and an open end, a piston on said rod and abutting said shoulder, means for holding said rod and piston in assembled relation, and an open ended tube in said rod closing the open end thereof from communication with said cylinder, and means including said rod and tube for conducting actuating fluid from a source of supply to opposite ends of said cylinder.
12. A machine of the character described 125 having, in combination, a percussive tool, feeding means therefor comprising a tubular sleeve carrying a piston and projecting from opposite ends thereof, a hollow piston rod carried by said sleeve and forming therewith 130

1. A shoulder, a tube in the hollow of said rod and carried by said sleeve, said tube closing one end of said sleeve from communication with said cylinder, and a nut on the end of 5 said sleeve holding said piston against said shoulder.
2. A machine of the character described having, in combination, a percussive tool, feeding means therefor comprising a tubular 10 sleeve having a reduced internal diameter portion, an open ended tube carried by said portion, a piston carried by said sleeve and having an end face spaced from the end of said sleeve to afford a projecting sleeve portion, and a hollow piston rod surrounding 15 said tube and carried by said projecting sleeve portion.
3. A machine of the character described, a percussive tool, fluid operated 20 feeding means for said percussive tool comprising a stationary cylinder, a piston in said cylinder, a substantially U-shaped hollow piston rod one leg of which extends from the rearward end of said cylinder and is connected to said piston, the other leg being connected to a valve casing carried by said percussive tool, said percussive tool being slidably supported by said feed cylinder by means independent of said rod, and a valve 25 in said valve casing controlling the admission of motive fluid to said cylinder by way of said hollow rod for actuation of said piston.
4. A machine of the character described, a drill operating device, a guide for 30 said device, fluid operated feeding means for moving said device along said guide, said feeding means comprising a stationary cylinder member and a movable piston member, a hollow substantially U-shaped piston rod projecting through the rear end of said cylinder and being in fluid communication therewith, means independent of said rod for connecting said device to said guide, a valve 35 casing connecting the end of said rod to the rearward end of said device, and a valve carried by said casing for controlling the admission and exhaust of motive fluid to and from said rod for actuation of said piston.
5. In a machine of the character described, a drill operating device, a guide for 40 said device, fluid operated feeding means for moving said device along said guide, said feeding means comprising a stationary cylinder member and a piston member, a hollow substantially U-shaped piston rod projecting through the rear end of said cylinder and being in fluid communication therewith, a tube in said rod extending substantially the full length thereof, said tube being 45 in fluid communication with the opposite end of said cylinder, a connection between said rod and the rearward end of said device, and a valve carried by said connection 50 for controlling the admission and exhaust of motive fluid to said rod and tube for actuation of said piston.
6. In a machine of the character described, a fluid operated tool actuator, a valve casing having a valve carried by said actuator for controlling the latter, a casing for 55 said valve, fluid operated means for feeding said actuator comprising a stationary cylinder and a piston in said cylinder, said cylinder slidably supporting said actuator, a substantially U-shaped rod in fluid communication with said cylinder and terminating in a valve casing detachably connected to the first mentioned valve casing and in fluid communication therewith, and a valve carried 60 by the valve casing in which said rod terminates for controlling the admission of motive fluid to said rod for actuation of said piston.
7. A hammer rock drill having, in combination, a percussive tool having provision 65 for carrying a drill steel, a feed cylinder containing a feed piston, a tube in fluid communication with said cylinder at one side of said piston, said tube having a bend and connecting said tool to said piston, said cylinder supporting said tool independently of said tube, a second tube, the latter being in fluid communication with said cylinder at the opposite side of said piston and carried 70 interiorly of said first mentioned tube in contact with the wall thereof at said bend.
8. A hammer rock drill having, in combination, a percussive tool having provision 75 for carrying a drill steel, a feed cylinder containing a feed piston, a tube in fluid communication with said cylinder at one side of said piston, said tube having a bend and connecting said tool to said piston, said cylinder supporting said tool independently of said tube, a second tube, the latter being in fluid communication with said cylinder at the opposite side of said piston and carried 80 interiorly of said first mentioned tube in contact with the wall thereof at said bend.
9. A rock drill having, in combination, a hammer drill comprising a casing having provision for carrying a forwardly projecting drill steel, a feed cylinder, a feed piston, means forming a feed piston rod, means other than said rod for operatively slidably connecting said casing and cylinder in side by side relation, said means forming said rod 85 having a portion projecting into the rear end of said cylinder and having a return portion spaced from the first mentioned portion, said return portion being operatively connected to said casing and being adapted to lie at the same side of said cylinder as said casing, and means for controlling the feeding of 90 said hammer drill comprising a pair of motive fluid conducting conduits in that portion of said means forming said rod which projects into said cylinder, said conduits being respectively in communication with said cylinder at opposite sides of said piston.
10. A rock drill having, in combination, a hammer drill comprising a casing having provision for carrying a forwardly projecting drill steel, a feed cylinder, a feed piston, a feed piston rod having a substantially U-shape, one leg of said U projecting into the rear end of said cylinder and being connected to said piston, the other leg of said U being operatively connected to said drill and being adapted to lie at the same side of said cylinder as said drill, means other than said rod for operatively slidably connecting said 100
11. A rock drill having, in combination, a hammer drill comprising a casing having provision for carrying a forwardly projecting drill steel, a feed cylinder, a feed piston, a feed piston rod having a substantially U-shape, one leg of said U projecting into the rear end of said cylinder and being connected to said piston, the other leg of said U being operatively connected to said drill and being adapted to lie at the same side of said cylinder as said drill, means other than said rod for operatively slidably connecting said 105
12. A rock drill having, in combination, a hammer drill comprising a casing having provision for carrying a forwardly projecting drill steel, a feed cylinder, a feed piston, a feed piston rod having a substantially U-shape, one leg of said U projecting into the rear end of said cylinder and being connected to said piston, the other leg of said U being operatively connected to said drill and being adapted to lie at the same side of said cylinder as said drill, means other than said rod for operatively slidably connecting said 110
13. A rock drill having, in combination, a hammer drill comprising a casing having provision for carrying a forwardly projecting drill steel, a feed cylinder, a feed piston, a feed piston rod having a substantially U-shape, one leg of said U projecting into the rear end of said cylinder and being connected to said piston, the other leg of said U being operatively connected to said drill and being adapted to lie at the same side of said cylinder as said drill, means other than said rod for operatively slidably connecting said 115
14. A rock drill having, in combination, a hammer drill comprising a casing having provision for carrying a forwardly projecting drill steel, a feed cylinder, a feed piston, a feed piston rod having a substantially U-shape, one leg of said U projecting into the rear end of said cylinder and being connected to said piston, the other leg of said U being operatively connected to said drill and being adapted to lie at the same side of said cylinder as said drill, means other than said rod for operatively slidably connecting said 120
15. A rock drill having, in combination, a hammer drill comprising a casing having provision for carrying a forwardly projecting drill steel, a feed cylinder, a feed piston, a feed piston rod having a substantially U-shape, one leg of said U projecting into the rear end of said cylinder and being connected to said piston, the other leg of said U being operatively connected to said drill and being adapted to lie at the same side of said cylinder as said drill, means other than said rod for operatively slidably connecting said 125
16. A rock drill having, in combination, a hammer drill comprising a casing having provision for carrying a forwardly projecting drill steel, a feed cylinder, a feed piston, a feed piston rod having a substantially U-shape, one leg of said U projecting into the rear end of said cylinder and being connected to said piston, the other leg of said U being operatively connected to said drill and being adapted to lie at the same side of said cylinder as said drill, means other than said rod for operatively slidably connecting said 130

cylinder and drill in side by side relation, and means for controlling the feeding of said drill comprising a pair of motive fluid conducting conduits formed in that leg of said rod which projects into said cylinder, said conduits respectively communicating with said cylinder at opposite sides of said piston.

21. A drilling machine having, in combination, a feed cylinder and a percussive tool slidably and nonrotatably connected in side by side relation for relative longitudinal movement, means providing a feed piston in said cylinder and a connected feed piston rod, said rod having a straight portion projecting from the rear end of said feed cylinder and a return portion connected to said percussive tool, both portions of said rod being substantially symmetrically disposed with relation to a plane passing through the axes of said cylinder and percussive tool, said rod comprising a hollow portion containing a tube, said hollow portion and said tube respectively being in communication with said feed cylinder at opposite sides of said pis-

ton, means for admitting motive fluid to 25 said hollow portion and said tube for effecting actuation of said feed piston.

22. A rock drill having, in combination, a percussive tool having provision for carrying a forwardly projecting drill steel, feeding means for said tool comprising a feed cylinder and means providing a feed piston and feed piston rod, said rod being substantially in the form of a U-shaped tube having one leg projecting into the rearward end of 30 said cylinder and the other leg operatively connected to said tool, passage means placing the interior of said rod in fluid communication with said cylinder at one side of said piston, a tube in said rod in fluid communication with said cylinder at the opposite side of said piston, means for supplying motive fluid to said tube and rod for effecting actuation of said feeding means, and means independent of said rod for slidably connecting 35 said cylinder and tool. 40 45

GEORGE H. GILMAN.
